Max D. Ordman
ATTORNEY

UNITED STATES PATENT OFFICE.

HERMAN H. MEYER, JR., OF NEW YORK, N. Y.

MEANS FOR SUPPORTING LAMPS.

Application filed February 21, 1923. Serial No. 620,475.

To all whom it may concern:

Be it known that I, HERMAN H. MEYER, Jr., a citizen of the United States, residing at New York, in the county of Bronx and 5 State of New York, have invented certain new and useful Improvements in Means for Supporting Lamps, of which the following is a specification.

The present invention relates to means for 10 supporting lamps, such as spotlight lamps on automobiles and has for its main object to provide a device, which may be applied to the wind shield, dash board or other upright part, so that the lamp can be easily and 15 conveniently manipulated from within a closed car to move the same to different positions.

The main object of my invention is to 20 simplify the construction of the device and thereby greatly reduce the cost of manufacture and the time necessary for mounting thereof.

With this and other objects in view my invention consists in the novel construction, 25 combination and arrangement of parts as will be hereinafter more fully described and defined in the appended claims.

In the accompanying drawing, in which similar reference characters denote corresponding parts, Fig. 1 is a perspective view 30 of a part of a closed car equipped with my new device; Fig. 2 is an enlarged section on line 2—2 of Fig. 1 and Fig. 3 is a section on line 3—3 of Fig. 2.

35 In the drawing 10 denotes a wind shield or other upright portion of an automobile. The same is formed with a circular opening 11 at a suitable place in front of the driver's seat in which opening the spotlight support 40 is adapted to be movably mounted. This support consists of a tubular, either solid or sectional, shaft or rod 12, the forward end of which is formed with the usual electric socket 13 for the electric bulb or spotlight

45 14 and the rear end of which is formed with a suitable electric switch 15 for said light and carries a handle 16 through which the electric wire connection 17 is passed and whereby the lamp can be manipulated.

50 Intermediate the ends of the tubular rod a ball 18 is provided of a size smaller than the hole 11 in the support 10, which ball is centrally perforated as at 18' to fit on and to be fastened to said rod 12. Thus far the construction of the device is well known.

55 The novel features of this invention re-

side in the means whereby the ball 18 will be durably held with the requisite tightness in its socket as to be properly centered and yet capable of free universal movements therein 60 and whereby the effects of wear and slackness in the joints will be greatly minimized.

This I accomplish by mounting on the ball meridially a resilient member in form of a ring 19 split at 19', which will have the tendency to tightly embrace the ball and which is adapted to serve as a socket for the latter. This ring is preferably stamped of thin resilient sheet metal, so as to form a channeled body, the side walls of which near and for a 70 short distance from the outer circumference are flat or substantially parallel to each other as 19² forming a centrally disposed circumferential rim and toward the inner circumference are bulging laterally forming 75 between themselves a V-shaped groove 19³, in which the ball is adapted to rest.

By virtue of the construction of the ring just described, the latter has a double resiliency, one in circumferential direction and 80 the other in axial direction. The ring 19 is so admeasured that when fully expanded it will loosely fit in the hole 11 of the part 10, and the circumferential rim 19² thereof in thickness is about equal to that of the wind shield or part 10. Adapted to be mounted on each side of the wind shield or part 10 is a ring 20 whose inner diameter is slightly larger than the meridian of the ball and bevelled at at 20' to bear against the bulging 90 portion of the adjacent wall of the ring 19. Both these rings are provided with perforations 20² for the passage of screw bolts 21, whereby they are joined together and tightened against the bulging parts of the ring 95 19. The ring 19 on its outer circumference is recessed as at 19⁴, the recesses being of semi-circular shape and considerably larger than the perforations 20² and spaced in conformity with the latter, so that the bolts 21 100 will freely pass therethrough, permitting the ring 19 to expand and contract. Ring gaskets 22 of fibre, leather or the like, the thickness or number of which may vary according to the thickness of the wind shield 105 used, are adapted to be inserted between each ring 20 and the wind shield 10 to permit the tightening of the rings 20 to the wind shield.

It will be seen that when the rings 20 are tightened their inner circumferences engage the bulging walls of the ring 19 compressing the latter axially and circumfer-

entially around the ball surface, thereby insuring a tight bearing of the ball, without, however, hindering its free movements.

What I claim and desire to secure by Letters Patent is:—

1. In a device of the character described, the combination with a support having a hole and a lamp support formed with a ball, of a socket therefor, comprising a channelled member formed with bent resilient parts adapted to engage around said ball and means for tightening said resilient parts on said ball.
2. In a device of the character described, the combination with a support having a hole and a lamp support formed with a spherical element, of a socket therefor comprising a channelled member meridionally mounted on said element and which has resilient laterally bent members engaging around circles of said element smaller than its meridian and means outside said hole for retaining said socket therein and tightening said member on said element.
3. In a device of the character described, the combination with a wind shield having a hole, and a lamp support provided with a spherical element to form a universal joint, of a socket for said element, comprising a resilient channelled split annular member meridionally mounted on said element and the side walls of which are bent laterally

and engage around circles of said element smaller than its meridian and annular means outside of said hole for retaining said socket therein and tightening said side walls on said element.

4. In a device of the character described, the combination with a wind shield having a hole, and a lamp support formed with a ball, of a channelled annular split member meridionally mounted on said ball and formed with bulging side walls, rings on the sides of said wind shield and adapted to engage said bulging walls and means for tightening said rings so as to lock said rings in position.

5. In a device of the character described, the combination with a wind shield, and a lamp support having a spherical element to form a universal joint, of a socket for said element comprising an annular member having bent resilient parts bearing on said element and rigid means adapted to be fixed to said wind shield and to engage said bent parts, so as to compress the latter and thereby retain said element within said socket.

In testimony whereof I affix my signature in presence of two witnesses.

HERMAN H. MEYER, JR.
